Adel Dommeville

UNITED STATES PATENT OFFICE.

ROLAND B. RESPESS, OF NEW YORK, N. Y., ASSIGNOR, BY MESNE ASSIGNMENTS, TO
RESPRO INC., OF CRANSTON, RHODE ISLAND, A CORPORATION OF RHODE ISLAND.

UNWOVEN STRING OR CORD AND PROCESS FOR MAKING THE SAME.

Application filed January 18, 1918. Serial No. 212,415.

To all whom it may concern:

Be it known that I, ROLAND B. RESPESS, a citizen of the United States and resident of the borough of Manhattan, city of New York, in the county of New York and State of New York, have invented certain new and useful Improvements in an Unwoven String or Cord and Process for Making the Same, of which the following is a specification.

This invention relates to an unwoven string or cord and the process for making the same, and is an improvement of my invention for an unwoven string or cord described in patent application, filed December 18th, 1917, Serial Number 207,783.

One of the objects of this invention comprises the production of a strong pliable string or cord of unwoven matted fibers having the appearance of leather, which may be finished in a manner similar to that employed for leather strings or cords. The strings or cords may be cut to suitable lengths and the ends thereof provided with metallic tips, or tips may be formed in the string or cord, which latter tips are treated to become stiff as described hereinafter. The strings or cords may also be given the appearance of woven or braided strings or embossed leather tapes, useful for the cords of shoes, corsets, upholstery and the like.

In general terms the process consists in first producing a fiber sheet of suitable vegetable, animal or mineral fibers, such as cotton, hemp, flax, ramie, jute, wool, hair, asbestos and the like, with the fibers thereof preferably located in the direction of the length of the sheet. The fiber sheet is formed in narrow widths by carding or other suitable machines or may be formed in wide sheets that are cut in strips or narrow sheets. The narrow sheet is treated in suitable machinery, by which one of its longitudinal edges is saturated with a solution of a binding agent. The sheet is then formed into a roll, the cross-section of which forms a spiral with the saturated edge forming the core of the roll, and the unsaturated portion wound around said edge and core. The spiral may be flattened so that each winding of the spiral becomes approximately elliptical in shape. The sheet may

be twisted to a helical shape. The cord or string so far produced is passed through coacting grooves formed on the surfaces of 55 rollers which are tangent to each other in the direction of their lengths. Each pair of grooves forms circular, oval or other shaped dies for the cord, and which I will designate hereinafter as forming dies. 60

The said forming dies compress the string or cord as it passes therethrough. After the string or cord has passed through a number of such forming dies, of consecutively decreasing diameters, it is saturated 65 with a binding agent, which causes the fibers to adhere to each other after being dried. After drying, the cord or string is again passed through other forming dies of consecutively decreasing diameters, to further 70 compress it, and then may again be treated with the binding agent and dried. The cord may next be passed through still smaller forming dies to be compressed to the requisite diameter. The string or cord 75 is next coated with surface dressing and passed through compression dies, which latter may be heated, after which the cord or string is cut into the required lengths. Before cutting, the string may at proper distances thereof be finished with a double metallic tip, by means of a tipping machine. The string or cord and the middle portions 80 of the double tips are then severed, so that lengths of cord or string are produced with 85 a tip at each end. Double tips may also be die-pressed in the string or cord, by means of a die, which compresses the string at different portions thereof. The said compressed portions may be finished with a coat- 90 ing agent, which when dry stiffens them, or the compressed portions may be surfaced with a coating of rubber and vulcanized. The compressed portions when cut in two, form non-metallic tips for the ends of the 95 lengths of the string or cord.

The accompanying drawings show an exemplification of apparatus to carry out the invention and in which Fig. 1 is a section of Fig. 2 on the line 1, 1; Fig. 2 represents a plan view of the apparatus to carry out the initial steps of making the string or cord and Figs. 3 and 4 show elevations partly in vertical section of apparatus to carry

out the other steps of the process and Fig. 5 shows an elevation partly in section on a larger scale of apparatus to carry out a modification of a part of the process.

5 A journal bearing is indicated at 20.

A bracket 21 is provided with journal bearings 22, 23 and 24. A shaft 25 is journaled in the bearings 20 and 22.

A pulley 26 is fastened to the shaft 25

10 at one end and a bevel gear 27 is fastened to the other end. A spindle 30 is journaled in the bearings 23 and 24 and has extending therefrom the tapered winding spindle 31.

A roller 34 is fastened to the shaft 25 and a

15 roller 35 is journaled in bearings not shown below the roller 34. Rollers 38, 39 and 40 carry the endless conveyor belt 41. The roller 40 is journaled in a tank 42, that contains a solution of a binding agent 43. A bracket

20 et 45 is attached to the tank 42 and has a guide opening 46 for the belt 41. An opening 47 has adjustably located therein the scraper 48. A flanged guide plate 50 has formed therein a recess 51 to enable the belt 41 to move in said recess.

A journal bearing 53 has fastened thereto a spur gear 54. A shaft 56 is journaled in the bearing 53 and extends through the spur gear 54. The shaft 56 has fastened thereto at one end the pulley 57 and at the other end, the hub 58 of the frame 59.

The frame 59 has formed therewith the stationary leg 60 and the hinged leg 61. A hub 62 extends from the frame 59. A pin 63 is supported in the hub 62 and has journaled thereon the combined bevel pinion 64 and spur gear 65. The latter meshes with the spur gear 54. A journal pin 66 extends from the frame 59 and has journaled thereon the combined spur gear 68 and bevel gear 69. The bevel gear 69 meshes with the bevel pinion 64. A shaft 73 is journaled in the legs 60 and 61. The said shaft has formed therewith the friction collar 75 and supports the loose collar 76. A pinion 77 on the shaft 73 meshes with the spur gear 68.

A spool 78 with the disc flanges 79 and 80 is supported on the shaft 73. Nuts 82, 83 are provided for the threaded ends of the shaft 73. By means of the nut 83 the friction between the disc flange 80 and friction collar 76 can be varied, which varies the speed of rotation of the spool 78. An arm 85 with the elliptical opening 86 extends from the hub 58.

The operation of the apparatus is as follows:

Raw cotton or the like in the form of unwoven fiber sheets 90 with the fibers thereof located in the direction of its length is located upon the guide plate 50 and is led between the rollers 34 and 35, the shaft 25 turning.

The conveyor belt 41 carries the binding agent 43 against the lower surface of the

sheets 90 and adjacent to one side edge thereof. The sheets 90 extend around the tapered spindle 31 forming a roll which becomes a string or cord, that passes through the opening 86 and around the spool 78.

The shaft 56 revolves and with it revolves the frame 59. During the revolutions of the frame, the spool 78 through the train of gears, turns on the shaft 73. The combined motion twists the fiber sheet 90 as it leaves the spindle 31 and winds it on the spool 78. This produces a twisted cord 92, the center of which is saturated with the binding agent which under the effect of the twisting may extend outwardly to or near the surface of the cord. The cord or string is next passed through forming dies 100 which compress it, and is next conveyed to a drying chamber 101, by which the rubber is set and the fibers bound together. The string or cord is then further compressed by means of forming dies 102. The string or cord 92 is next treated with a binding solution 103 in a tank 104 that may be composed of the following:

Rubber gum dissolved in naptha or benzol to make a three percentum solution; to one gallon of this solution is added one-third ounce of balata, which latter has been dissolved by a suitable solvent, and to which is added one sixth ounce of glue, one sixth ounce of sulphur, one third ounce of white lead and one sixth ounce of linseed oil.

The proportions of the ingredients of this binding agent may be varied to produce either a stiff flexible string or cord, or one that is soft and flexible. The string or cord is then again dried in a drying chamber 106 to evaporate the naptha or other liquids thereof, after which it is again compressed by means of forming dies 107 to the required diameter.

The string or cord 92 is then surfaced with a suitable dressing 108 in a tank 109 and passed through a pair of heated forming dies 110. The raw cotton before being formed into sheets may be treated with a dyeing agent, to obtain the color required for the finishing product.

The binding agent may also have introduced therein a coloring agent. The last forming dies through which the string or cord is passed may be either circular, oval or of other forms, and the heated finishing dies may contain a graining design to produce a cord or string resembling a woven or plaited string or cord. After the string has been run through the heated dies it may be tipped with metallic tips 115 by means of dies 116 or compressed tips 118 as already described, may be formed in the string by means of similar dies 116a.

The latter tips may be coated by means of a brush 120 with an agent to stiffen them or they may be coated with rubber and vulcanized before being cut in two, forming a pressed tip at each end of the lengths of the

finished string or cord. While the string is being coated with the brush 120 it may be supported on the table 121.

Having described my invention what I desire to secure by Letters Patent and claim is:

1. The herein described process consisting in forming a sheet of matted fibers, saturating one of the longitudinal edges of the sheet with a binding agent, folding the sheet over this edge as a core and compressing the product.

2. The herein described process consisting in forming a sheet of matted fibers, saturating one of the longitudinal edges of the sheet with a binding agent, folding the sheet over this edge as a core, compressing the product to the diameter desired, surfacing the string produced with suitable dressing and subjecting it to heat.

3. The herein described process consisting in forming a sheet of matted fibers, saturating one of the longitudinal edges of the sheet with a binding agent, folding the sheet over this edge as a core, compressing the product, saturating it with a binding agent to cause the fibers to adhere to each other when dried, compressing the product, surfacing the string produced, with a dressing, heating securing to the string at different portions thereof, a metallic covering and cutting the string in lengths and the metallic covering in half to form a tip at each of the ends of the lengths of string.

4. The herein described process consisting in forming a sheet of matted fibers, sat-

urating one of the longitudinal edges of the sheet with a binding agent, folding the sheet over the edge as a core, compressing the string produced, saturating the string with a binding agent to cause the fibers to adhere to each other when dried, compressing the string to a reduced size, surfacing the string with a dressing, heating, compressing the string at different portions to form tips and cutting the compressed portions in two to form a tip at each end of the lengths of the strings formed by the cutting.

5. The herein described process consisting in forming a sheet of matted fibers, saturating one of the edges thereof with a binding agent, folding the sheet over the edge as a core, compressing the folded sheet to form a string, saturating it with a solution consisting of rubber, naptha, balata, glue, white lead, sulphur and linseed oil, drying and compressing the string to gradually reduce the size thereof.

6. A string consisting of a sheet of matted fibers rolled on one of the edges thereof, a binding agent to hold the fibers of the string together, a dressing for the surface of the string and tips for the ends thereof.

Signed at the borough of Manhattan city of New York in the county of New York and State of New York this 9th day of January A. D., 1918.
